By Knight Bros Attest.

UNITED STATES PATENT OFFICE.

FREDRICH BURCKHARDT, OF ST. CHARLES, MISSOURI.

BOLTING-REEL ATTACHMENT.

SPECIFICATION forming part of Letters Patent No. 313,988, dated March 17, 1885.

Application filed June 21, 1884. (No model.)

To all whom it may concern:

Be it known that I, FREDRICH BURCKHARDT, of St. Charles, in the county of St. Charles and State of Missouri, have invented 5 a certain new and useful Improvement in Bolting-Reel Attachments, of which the following is a full, clear, and exact description, reference being had to the accompanying drawings, forming part of this specification, and 10 in which—

Figure 1 is a vertical transverse section of a flour-bolt having my improvement, taken on line 1 1, Fig. 2; and Fig. 2 is a side elevation with part of the casing or housing removed.

15 My invention relates to an attachment for cleaning the cloth of the reel automatically; and my invention consists in features of novelty hereinafter fully described, and pointed out in the claims.

20 Referring to the drawings, A represents a bolting-reel of ordinary construction inclosed within a common casing or housing, B. Secured to the heads A' of the reel are pins or projections C, preferably one (on each disk) 25 at each corner of the reel, as shown in Fig. 2.

D represents a knocker consisting, preferably, of a brush, supported on the free ends of arms I, hinged to the housing, as shown at I', one at each end of the reel. These arms

are held against the pins C as the reel revolves by springs J; but the pins hold the arms far enough back for the knocker not to come in contact with the reel, except when the pins come opposite depressions or notches L in the arms, and then the springs force the 35 arms inward, causing the knocker to strike the cloth of the reel to clean it. The depressions or notches are quite short, so that as soon as the knocker strikes the reel it is forced outward or back again, so as not to rub on 40 the reel.

My improved knocker will thus keep the reel or the cloth of the reel perfectly clean at all times.

I claim as my invention—

45 The combination, with a reel armed with pins or projections, of the hinged arms formed with depressions or notches to receive the pins or projections, and a brush secured to the free ends of the arms, the brush being arranged to strike the reel-cloth when the pins or projections enter the depressions or notches in the arms, as set forth.

FREDRICH BURCKHARDT.

In presence of—

GEO. H. KNIGHT,
SAM'L. KNIGHT.
